(73) Assignee: Good Humor-Breyers Ice Cream, division of Conopco, Inc., Green Bay, WI (US)

(57) CLAIM

The ornamental design for a food product, especially an ice cream cake, as shown and described.

DESCRIPTION

FIG. 1 is a perspective view of a food product, especially an ice cream cake showing our new design;

FIG. 2 is a front elevational view thereof;

FIG. 3 is a rear elevational view thereof;

FIG. 4 is a side elevational view thereof;

FIG. 5 is another side elevational view thereof, opposite FIG. 4;

FIG. 6 is a top plan view thereof; and,

FIG. 7 is a bottom plan view thereof.

() Term: 14 Years
